CLAIM

The ornamental design for a beach umbrella and staked blanket combination, as shown and described.

DESCRIPTION

FIG. 1 is a front elevation view of a beach umbrella and staked blanket combination showing my new design with stakes and blanket shown separately for clarity of illustration;

FIG. 2 is a rear elevation view thereof;

FIG. 3 is a right elevation view thereof;

FIG. 4 is a left elevation view thereof;

FIG. 5 is a top plan view thereof; and,

FIG. 6 is a bottom plan view thereof.

1 Claim, 6 Drawing Sheets
